UNITED STATES PATENT OFFICE

ARTHUR W. CATLIN, OF CHICAGO, ILLINOIS, ASSIGNOR TO BRADLEY PULVERIZER COMPANY, OF ALLENTOWN, PENNSYLVANIA, A CORPORATION OF MASSACHUSETTS

TUBE MILL

Application filed September 27, 1930. Serial No. 484,885.

This invention relates to improvements in tube mills of the type comprising a drum having means for introducing the material to be ground at one end, and means for discharging the ground material from the drum at the other end, grinding members, such as balls, pebbles, rods, etc., being provided within the drum to aid in the pulverizing operation.

In usual constructions the ground material is treated by a classifier or separator to remove the material ground to a predetermined degree of fineness, and the tailings are returned to the inlet end of the mill where they are re-ground. Any considerable quantity of these relatively fine tailings will cushion the action of the grinding bodies and, therefore, delay the grinding action.

The present invention relates to improvements in mills of the type described which comprise the provision of means for returning the tailings to the grinding mill at any desired position longitudinally of the drum, so that the cushioning effect of the tailings upon the coarser material, during the initial grinding operation, will be avoided and the rapidity of the grinding action will, therefore, be accelerated.

The invention may also be employed for the purpose of introducing into the mill a substance of another character than that which is fed into the mill, such, for example, as the addition of gypsum to the clinker being pulverized during the production of Portland cement.

The invention may be employed for introducing material, such as tailings, or other suitable material, at a predetermined distance from the inlet end of a tube mill having a single grinding compartment, but is especially adapted for application to a compartment mill in which the drum is separated by one or more screen diaphragms to provide a plurality of compartments which are provided respectively with progressively small grinding members. In such constructions means are provided for returning the tailings, or delivering other material, to any compartment, or any position within the mill, preferably a compartment other than the

first or initial grinding compartment, so that the tailings, or such other material will be mixed with the original material of substantially the same degree of fineness, or of the same degree of hardness, or grindability.

Any suitable means may be provided for delivering the tailings, or other material, to the drum or any compartment thereof. Preferably, however, such means comprises a tubular conduit extending into the drum through one or both of the hollow trunnions upon which the drum is mounted, with means for causing the material to travel lengthwise of the conduit, and suitable ports having gates selectively operable to cause the material to be delivered into the drum, or to a selected compartment thereof at a predetermined distance from its inlet or outlet end.

In accordance with the present invention the conveyer or conduit may extend into the drum through either or both of the tubular trunnions thereof, and suitable means, such as a screw, may be employed for causing the tailings, or other material, to travel through the conduit. Desirably the conduit may be so connected to the drum as to rotate therewith and provided with a spiral screw or plate rigidly secured within the conduit and having a proper pitch to cause the material to travel longitudinally of the conduit during its rotation with the drum.

Preferred embodiments of the invention are illustrated in the accompanying drawings, in which,

Fig. 1 illustrates, mainly in longitudinal vertical section, a single compartment tube mill and provided with an air separator, with means for returning the tailings from the separator to the conveyer which delivers the same to the drum at any one of a plurality of selected positions longitudinally of the drum;

Fig. 2 is a transverse sectional view of the tubular conduit on line 2-2, Fig. 1;

Fig. 3 is a transverse sectional view of a modified form of armored tubular conduit;

Fig. 4 is a view showing mainly in longitudinal section a tube mill having a series of grinding compartments, and also illustrating an air separator together with means for returning the tailings through the outlet end

of the grinding mill to any selected compartment at any predetermined distance from the inlet end of such compartment; and,

Fig. 5 is a longitudinal sectional view of a 5 grinding mill illustrating means for introducing tailings, or other material, into the mill at any desired distance from the inlet end thereof through a conveyer extending through the tubular trunnion forming the inlet 10 let through which the material is fed to the mill and adapted to deliver the tailings to the drum at any predetermined distance from the inlet end of the drum.

The present invention is designed for the 15 purpose of speeding up production of Portland cement and other finely ground material produced from rock, ore, etc., or relatively large masses of other material, by treatment in a novel manner during the reducing process 20 in a tube mill which may or may not be provided with compartments. Means are provided to return the partly finished material to any desired section of the tube, or to any particular compartment thereof to permit 25 finishing of the material in the most efficient manner.

By the employment of the present invention to return the tailings or to add other materials to the primary material being 30 ground at such position lengthwise of the drum as to commingle it with material of substantially the same fineness, or of the same grindability, the cushioning effect upon the larger grinding balls acting initially upon 35 the material is avoided and the rate of production of finely ground material is very considerably increased. Furthermore, greater uniformity in the product discharged from the delivery end of the drum is obtained.

40 The construction illustrated in Fig. 1 comprises a cylindrical metallic drum 1 having its ends abutting against heads 2 and 3 which are provided respectively with preferably integral hollow trunnions 4 and 5 which are 45 mounted in suitable, preferably hollow, bearings 6 and 7 in standards 8 and 9. The ends of the drum are secured to the heads, preferably by angle iron plates 10 and 11 which are welded, riveted, bolted, or otherwise secured 50 to the drum and to the head. The driving gear 12, which is secured to the angle plates 11 and head 3, is actuated in the usual manner by a pinion (not shown) driven in any suitable manner as is usual in such constructions. 55 The hollow trunnion 4 provides an inlet through which the material to be ground may be introduced into the drum, and the hollow trunnion 5 provides an outlet through which the ground material is delivered from 60 the drum.

A scoop 13, connected to the end of the hollow inlet trunnion 4, and provided with a mouth 14 adapted to pass through a feed box 15, provides means for feeding the material 65 into the drum. The material is discharged

from the outlet trunnion 5 into a box 16 from which it passes through a suitable conduit 17 to an elevator 18, or any other transport system, which delivers the ground material to the inlet 19 of an air separator 20, preferably of the type disclosed in the patent to Gibson and Needham No. 1,346,015, July 6, 1920. However, the material may be delivered to any other type of separator or classifier having means for returning the tailings to the 75 grinding mill.

As illustrated in the accompanying drawings the tailings pass from the air separator 20 through a pipe 21 to a suitable conveyer operable to deliver the tailings to the drum 80 at any desired predetermined distance from the inlet end of the drum. In the preferred construction the conveyer comprises a tubular metallic conduit 22 having a series of ports 23 spaced at desired distances longitudinally of the conduit. Inasmuch as the wall of the conduit may be subject to abrasion of the contents of the drum, it desirably may be armored by a series of cylindrical separate plates 24 secured to the wall of the conduit 22 and provided with ports 25 coinciding with the ports 23.

Suitable adjustable gates are provided for causing the material to be discharged from the conduit at any desired predetermined distance from the inlet end of the drum. The particular form of gates illustrated in the accompanying drawings comprises cylindrical sleeves 26 adapted to fit snugly the exterior of the conduit 22. The sleeves 26 are adjustable along the conduit 22 to control the flow of material out of the ports 23. The ends of the conduit 22 may be supported in any suitable manner, as, for example, by spiders 30 in the hollow inlet trunnion 4, and such other spiders as may be required, located at suitable distances apart longitudinally of the drum. The drum is provided with a usual lining 31 which may, if desired, be provided with ribs 32. An annular wear plate 33 is provided at the inlet end of the drum, and the discharge end of the drum is provided with a preferably slotted screen diaphragm 34, the periphery of which engages the drum 1 and the face of which abuts against the lining 31.

In the operation of the machine the material to be ground is fed into the box 15 from which it is scooped up by the scoop 13 and fed into the mill through the hollow trunnion 4. It is subjected to the grinding action of the usual grinding members, such as balls, pebbles, rods, etc., and the ground material passes through the screen diaphragm, which serves to prevent discharge of the grinding members, thence passes through the drum to the box or hopper 16 from which it passes through the conduit 17 to the elevator, or other suitable conveyer.

The material is discharged from the elevator into the inlet 19 of the separator or other 130

classifier 20 and the finely ground material is drawn off from the separator through the discharge conduit 35. The tailings are returned through the pipe 21 to the conduit 22 from which it is carried to the desired open port which returns it to the drum.

Suitable means may be provided for causing the material to travel lengthwise of the conduit 21, such, for example, as a screw or spiral flight or flights 36 within the conduit.

The screw may be rigidly secured to the conduit to rotate therewith, as illustrated, or may be driven by a separate source of power, as will be readily understood. By securing the screw or spirals to the wall of the conduit the drum, conduit and screw are rotated in unison, thereby avoiding the necessity of providing additional power for driving the screw, and thus reducing the expense of operation of the machine.

Any of the sleeves 26 may be adjusted to cause the tailings to be delivered at a desired distance from the intake end of the grinding drum, so that the tailings discharged into the drum will be of substantially the same degree of fineness or grindability as the other material which is being treated within the drum at the position at which the tailings are added to it, thereby avoiding the cushioning effect of the tailings which otherwise would be produced if delivered into the drum at the intake end thereof.

Obviously the conduit 23 may terminate at any desired point within the drum and the material delivered either from the end of the conduit or through an open port intermediate of its length. In such case the free end of the conduit would, of course, be supported upon a suitable spider.

The position at which it is desirable to introduce the tailings into the drum may be dependent upon the character of the material being ground and in the assembling of the mill a proper gate or sleeve may be slidably adjusted or removed to permit the material to be discharged at the desired distance from the inlet end of the drum.

By reason of the present invention, therefore, a construction is provided which can be readily adapted to rapid grinding of different materials.

The invention is illustrated in Fig. 4 of the drawings as applied to a compartment tube mill. In one form, the drum comprises a main cylindrical portion 37 and a preferably enlarged initial section 38 having a tapered portion 39 merging into the main portion 37 of the drum. The drum is secured to heads having integral trunnions 40 and 41, of the character above described, providing respectively an inlet for the material to be ground and an outlet for the ground material. The trunnions are mounted respectively in bearings upon standards 42 and 43 and the drum is rotated by a gear 44 secured to the main

portion of the drum in the manner heretofore described.

A screen diaphragm, or preferably screen diaphragms 45 and 46 serve to separate the enlarged initial grinding compartment 47 from the chamber of the main portion 37 of the drum. One or more screen diaphragms, or pairs of screen diaphragms 48, divide the chamber of the main drum into a series of compartments 49 and 50, etc.

Large grinding members, such as balls 51, are provided in the first or initial grinding compartment, while progressively smaller balls 52 and 53, etc., are provided in the succeeding compartments 49 and 50, etc., of the mill. The material to be ground is fed into a box 54 from which it is carried by the usual scoop 55 secured to the hollow trunnion 40 and delivered through the hollow trunnion into the initial grinding compartment of the mill where it is acted upon by the large grinding members 51. The material passes from this compartment through the screen diaphragms 45 and 46 into the next compartment, where it is acted upon by the smaller grinding members 52, and thence through the screen diaphragms 48 to the compartment 50 containing the still smaller balls 53. The material is delivered from the compartment 50 through a screen diaphragm 56 and discharged through the tubular trunnion 47 into a box or hopper 57 having a conduit 58 leading to an elevator 59, or other conveyer.

The elevator 59 discharges the material into the inlet 60 of an air separator or other classifier 61 from which the fine material is delivered through the outlet 62 and the tailings are returned to the mill through a chute 63. Any other desired means may be employed to handle and return the material after it has passed through the mill during and after the classifying process. The lower end of the chute 63 communicates with a tubular conduit 64 having at intervals ports 65 which are provided with gates, such as adjustable and detachable sleeves 66 of the character above specified. Any suitable number of ports with gates may be provided and the sleeves or gates may be slid longitudinally upon the conduit or removed therefrom to provide an open port, such as a port 67 for delivering the tailings at any desired predetermined distance from the inlet end of any compartment. Preferably the material is not delivered to the initial grinding compartment and the end of the conduit 64 may, therefore, be mounted in the diaphragms 45 and 46.

The diaphragm or diaphragms 48 may be placed at any suitable distance from the intake end of the main portion of the drum to divide the same into compartments of such suitable length as may be required to produce the desired grinding action.

A screw or spiral flight 68, which extends longitudinally of the conduit 64, and which

preferably is rigidly secured therein in the manner previously described, may be employed to cause the tailings to travel longitudinally of the conduit. In this construction, as in the construction previously described, the conduit 66 extends axially through the hollow outlet trunnion 47 and is rigidly secured thereto by a spider 69.

In Fig. 5 a modified construction is shown in which the drum 70 illustrated is, and may be similar to, that shown in Fig. 1, and is similarly mounted and actuated. In this construction, however, the tubular conduit 71 is mounted at both ends in a spider 72 in the tubular inlet trunnion 73 and outlet trunnion 74. A screw 75 serves to deliver the material from the feed box 76 through the tubular inlet trunnion 73 to the drum, the material being delivered from the drum through the tubular outlet trunnion 74. In this construction the cylindrical conduit 71, which is provided with a longitudinal series of ports 77, with detachable or adjustable sleeves or gates 78 therefor, is provided with a screw 79 of opposite pitch to that illustrated in the preceding figures, and the tailings, or other material, are delivered to the conduit at the inlet end of the drum through a suitable hopper 80, a chute 81 leading to the conduit 71, so that in this construction the tailings, or other material, are introduced into the conduit 71 at the inlet end of the drum and travel in the same direction as the direction of movement of the material being ground. In this construction, as in the constructions previously described, any one of the gates may be opened or removed to permit the delivery of the tailings, or other material, into the drum at a desired distance from the inlet end thereof for the purposes heretofore described.

It is to be understood that the embodiments of the invention disclosed herein are of an illustrative character, and are not restrictive, and that the invention may be applied to other types of tube, ball, or rod mills to which it may be applicable.

Having thus described the invention, what is claimed as new, and desired to be secured by Letters Patent, is:

1. A tube mill comprising a rotatable grinding drum having hollow trunnions at its ends providing respectively an inlet for the material to be ground and an outlet for the ground material, means for feeding the material into the drum through said inlet trunnion, auxiliary means for introducing material into said drum including a conveyer of smaller diameter than the hollow trunnions, extending concentrically through one of said hollow trunnions into and longitudinally of said drum, and having means for delivering the material into the drum at a predetermined distance from the inlet end of the drum.

2. A tube mill comprising a rotatable grinding drum having hollow trunnions at its ends providing respectively an inlet for the material to be ground and an outlet for the ground material, means for feeding the material into the drum through said inlet trunnion, auxiliary means for introducing material into said drum including a conveyer, extending through one of said hollow trunnions into and longitudinally of said drum, and having a plurality of means selectively operable to deliver the material from said conveyer to said drum at different predetermined distances from the inlet end of said drum.

3. A tube mill comprising a rotatable grinding drum having hollow trunnions at its ends providing respectively an inlet for the material to be ground and an outlet for the ground material, means for feeding the material into the drum through said inlet trunnion, auxiliary means for introducing material into said drum including an armored tubular conveyer, extending concentrically through one of said hollow trunnions into and longitudinally of said drum and rotatable therewith, and having a plurality of means selectively operable to deliver the material from said conveyer to said drum at different predetermined distances from the inlet end of said drum.

4. A tube mill comprising a rotatable grinding drum having hollow trunnions at its ends providing respectively an inlet for the material to be ground and an outlet for the ground material, means for feeding the material into the drum through said inlet trunnion, auxiliary means for introducing material into said drum including a tubular conduit extending through one of said hollow trunnions into and longitudinally of said drum and provided with a screw for causing the material to travel therethrough and with a plurality of ports, and adjustable gates for said ports selectively operable to deliver the material from said conduit to said drum at different predetermined distances from the inlet end of said drum.

5. A tube mill comprising a rotatable grinding drum having hollow trunnions at its ends providing respectively an inlet for the material to be ground and an outlet for the ground material, means for feeding the material into the drum through said inlet trunnion, auxiliary means for introducing material into said drum including a tubular conduit extending concentrically through one of said trunnions into and longitudinally of said drum and connected to and rotatable with said drum, a screw extending longitudinally of said conduit and rotatable therewith, said conduit being provided with a plurality of ports and adjustable gates for said ports selectively operable to deliver the material from said conduit to said drum at different

predetermined distances from the inlet end of said drum.

6. A tube mill comprising a rotatable grinding drum having hollow trunnions at its ends providing respectively an inlet for the material to be ground and an outlet for the ground material, means for feeding the material into the drum through said inlet trunnion, means dividing said drum into a plurality of compartments, auxiliary means for introducing material into said drum including a tubular conduit extending longitudinally of said drum and concentrically through one of said trunnions and said screen-
15 ing means, said conduit being provided with a plurality of ports and adjustable gates for said ports selectively operable to deliver material from said conduit to a selected compartment at a predetermined distance from the end of such compartment.

7. A tube mill comprising a rotatable grinding drum having hollow trunnions at its ends providing respectively an inlet for the material to be ground and an outlet for the ground material, means for feeding the material into the drum through said inlet trunnion, screen diaphragms extending transversely of the drum dividing the same into a plurality of compartments, auxiliary means for introducing material into the drum comprising a tubular conduit extending concentrically through one of said hollow trunnions and also concentrically through said screen diaphragms and secured thereto, means operable by the rotation of the drum to cause the material to travel longitudinally of said conduit, said conduit having a longitudinal series of ports, sleeve gates for said ports slidably and adjustably mounted on said conduit and respectively operable to discharge the material into a selected compartment at predetermined distances from the inlet end of said compartment.

8. A tube mill comprising a rotatable grinding drum having hollow trunnions at its ends providing respectively an inlet for the material to be ground and an outlet for the ground material, means for feeding the material into the drum through said inlet trunnion, a tubular conduit extending concentrically through the delivery trunnion into and longitudinally of the drum and having a series of ports, a separator for the ground material discharged from the outlet trunnion, means for returning the tailings from said separator to said conduit, means for causing the tailings to travel longitudinally of said conduit, and gates for said ports selectively operable to deliver the tailings from said conduit to the drum at different predetermined distances from the inlet end of the drum.

9. A tube mill comprising a rotatable grinding drum having hollow trunnions at its ends providing respectively an inlet for the material to be ground and an outlet for the

ground material, means for feeding the material into the drum through said inlet trunnion, screen diaphragms dividing the drum into a plurality of compartments, a tubular conduit extending concentrically through said delivery conduit and said diaphragms, and secured thereto, and provided with a longitudinal series of ports communicating with the respective compartments at intervals, a separator or other classifier for the ground material discharged from said outlet trunnion, means for returning the tailings from said separator or classifier to said conduit, a screw in said conduit operable to cause the tailings to travel longitudinally thereof, sleeves slidably adjustable on said conduit forming gates selectively operable to cause the material to be delivered to a selected compartment at a predetermined distance from the inlet end thereof.

10. A tube mill comprising a rotatable grinding drum having hollow trunnions at its ends providing respectively an inlet for the material to be ground and an outlet for the ground material, means for feeding the material into the drum through said inlet trunnion, screen diaphragms dividing the drum into a plurality of compartments, a tubular conduit extending concentrically through said delivery conduit and said diaphragms, and secured thereto, and provided with a longitudinal series of ports communicating with the respective compartments at intervals, a separator for the ground material discharged from said outlet trunnion, means for returning the tailings from said separator to said conduit, a screw fixedly secured in said conduit operable by the rotation of the conduit to cause the tailings to travel longitudinally thereof, and sleeves slidably adjustable upon said conduit forming gates for said ports selectively operable to cause the material to be delivered to a selected compartment at a predetermined distance from the inlet end thereof.

In testimony whereof, I have signed my name to this specification.

ARTHUR W. CATLIN.
